(57) **CLAIM**

The ornamental design for a flying disc toy, as shown and described.

DESCRIPTION

FIG. 1 is a top perspective view of the flying disc toy shown my new design:

FIG. 2 is a top plan view thereof:

FIG. 3 is a side elevation view thereof, the opposite side, front and rear are identical thereto; and,

FIG. 4 is a bottom view thereof.

The broken lines in FIG. 4 represent boundaries, the area within which forms no part of the claimed design.

1 Claim, 2 Drawing Sheets

FIG. 1

FIG. 2
